(57) **CLAIM**

The ornamental design for a tactical ring, as shown and described.

DESCRIPTION

FIG. 1 is a perspective view of a tactical ring our new design.

FIG. 2 is a front view of the tactical ring.

FIG. 3 is a rear view of the tactical ring.

FIG. 4 is a right view of the tactical ring.

FIG. 5 is a left view of the tactical ring.

FIG. 6 is a top view of the tactical ring.

FIG. 7 is a bottom view of the tactical ring.

FIG. 8 is a perspective view of the tactical ring, illustrating an insert coupled at a coupling slot of the tactical ring.

FIG. 9 is a perspective view of a first modification of the tactical ring our new design.

FIG. 10 is a front view of the first modification of the tactical ring.

FIG. 11 is a rear view of the first modification of the tactical ring.

FIG. 12 is a right view of the first modification of the tactical ring.

FIG. 13 is a left view of the first modification of the tactical ring.

FIG. 14 is a top view of the first modification of the tactical ring.

FIG. 15 is a bottom view of the first modification of the tactical ring.

FIG. 16 is a perspective view of the first modification of the tactical ring, illustrating an insert coupled at a coupling slot of the tactical ring.

FIG. 17 is a perspective view of a second modification of the tactical ring our new design.

FIG. 18 is a front view of the second modification of the tactical ring.

FIG. 19 is a rear view of the second modification of the tactical ring.

FIG. 20 is a right view of the second modification of the tactical ring.

(Continued)

FIG. 21 is a left view of the second modification of the tactical ring.
FIG. 22 is a top view of the second modification of the tactical ring.
FIG. 23 is a bottom view of the second modification of the tactical ring.
FIG. 24 is a perspective view of the second modification of the tactical ring, illustrating an insert coupled at a coupling slot of the tactical ring.
FIG. 25 is a perspective view of a third modification of the tactical ring our new design.
FIG. 26 is a front view of the third modification of the tactical ring.
FIG. 27 is a rear view of the third modification of the tactical ring.
FIG. 28 is a right view of the third modification of the tactical ring.
FIG. 29 is a left view of the third modification of the tactical ring.
FIG. 30 is a top view of the third modification of the tactical ring.
FIG. 31 is a bottom view of the third modification of the tactical ring; and,
FIG. 32 is a perspective view of the third modification of the tactical ring, illustrating an insert coupled at a coupling slot of the tactical ring.
The broken lines represent portions of the tactical ring that form no part of the claimed design. The broken lines in FIGS. 8, 16, 24, and 32 depict environmental subject matter that form no part of the claimed design.

1 Claim, 16 Drawing Sheets
